United States Patent Office.

GARRET D. ANDERSON, OF MONTROSE, NEW YORK.

Letters Patent No. 81,723, dated September 1, 1868.

IMPROVEMENT IN LIQUID-SAFE.

The Schedule referred to in these Letters Patent and making part of the same.

TO ALL WHOM IT MAY CONCERN:

Be it known that I, GARRET D. ANDERSON, of Montrose, in the county of Westchester, and State of New York, have invented a new and improved Oil and Liquid-Safe; and I do hereby declare that the following is a full, clear, and exact description of the same, reference being had to the annexed drawing, which forms part of this specification.

My invention consists in the construction of a metallic tank, for containing oil or other inflammable liquid, with a bottom so formed that the same shall incline from two sides to a central point, where a depression or groove is formed, which increases in depth to the point where the faucet enters the same, whereby I am enabled to construct the tank with fewer seams than has hitherto been done, and at the same time provide a tank from which all the oil or other liquid it contains can be drawn off, and without liability of the sediment collecting at any point, to impede the perfect flow of the liquid from the safe.

It also consists in the combination, with a tank so formed, of an enclosing case of wood, metal, or other suitable material.

It further consists in the combination, with such tank and its enclosing case, (whether the latter be of wood or other material,) of a lining or filling of fire-proof material, so that if the outer case be made of wood, and the same burn up, the tank will still be protected, and so that if the outer case be made of metal, the heat will be prevented reaching the inner case, to fire the oil or other inflammable liquid contained therein.

In the accompanying drawing—

Figure 1 represents a vertical central section through the safe, taken on the plane of the line x x , fig. 2, and

Figure 2 is a diminished view of the bottom of the same, introduced more especially to show the formation of the groove for draining the tank.

A designates an enclosing case or box, of any suitable form, and of any suitable material. In the present instance, it is shown as being constructed of wood, and of rectangular form. This box is provided with an opening at its top, and a lid or door, a , to close said opening.

B is a metallic tank, enclosed in the case A, and it is also provided with an opening at its top corresponding with the opening in the case A; and b is a neck secured to said tank around the opening, which neck passes up through the case A, and is provided with a metallic lid or cover, c , fitted inside the lid or cover a .

The manner in which this tank is constructed constitutes one part of my invention. One principal object has been to construct the tank with as few seams as possible, not only to save in expense, but to prevent leakage, which is always a contingency occurring at the seams of a liquid-vessel. I have shown the body of the tank as containing but two seams all round, which occur where the sides of the tank are secured to the part shown by the blue line in fig. 1. To explain: a strip of sheet metal, of the width it is desired to have the tank, is taken, and one end placed so that its edge will form one side of the mouth of the tank. It is then bent as shown at h i j k l , and, by making the tank in this manner, five joints are dispensed with. To this frame, plates of the proper size and shape are applied, and the joints made liquid-tight all round. It will thus be seen that there are but two seams all round.

I have described and shown this as a desirable way of making the tank; but I do not limit myself thereto, as joints might be made at the points h i k l , and then the bottom would be made with fewer joints than in any oil-tank heretofore constructed.

The bottom of a tank, if constructed with the joints h i k l , would consist of inclined plates or surfaces, extending from the point of junction with the sides to a central point, (see fig. 2.) By such construction there would be no seam in the bottom except where the same joins the sides.

A depression or groove, d , is made in the bottom, (see fig. 2,) which increases in depth as it approaches the side of the tank at the point where the faucet e enters it. It will therefore be seen that all the contents of the tank can be drawn off, and that the sediment will have but little chance to clog up the discharge-orifice of the tank, the same having a free chance to escape.

C is a lining or filling of some fire-proof material or substance, placed outside the tank B. In the present instance, the said filling is interposed between the tank B and the enclosing case A, the ensealing case being, of course, in cases where this filling is to be used, made sufficiently larger than the tank to admit of its introduction. This filling may be of any material suitable for the purpose, and applied in any suitable way.

Should the enclosing case be made of wood, and get on fire, it may all be consumed, and yet the tank be protected. Should the enclosing case, on the other hand, be made of metal, the filling will prevent heat from injuring the tank, and should the fire-proof material be secured to the outside of the tank B, the same object will be gained.

It will be noticed that the cover of the tank is also provided with a fire-proof filling.

For greater security, I will mention that the faucet may be provided with a screw-cap, and in such case, if the tank be filled with a highly-inflammable liquid, there would be less danger than with an ordinary faucet.

I do not limit my invention to the construction of an oil-safe with this filling, as a tank such as I have described can be made and used without it, and it may be used with or without the enclosing case.

I am aware that an oil-safe, consisting of a metallic tank enclosed in a wooden case, is not new, the same being shown in a patent granted to E. L. Allen, on the 8th of May, 1866; but I wish it to be distinctly understood that the construction of the tank shown in that patent and in my present application is entirely different. The bottom of that tank is made like a hopper, the said bottom being constructed of four triangular-shaped pieces of metal, inclined to a central point, and united by four joints where the pieces are soldered together, and said bottom is also soldered to the sides, making eight seams at the bottom. The discharge-orifice is at the centre of the bottom, a lead pipe connecting it with the faucet. I have found, by practice, that with the Allen safe, (and I state this without any desire to disparage the invention of another party, but simply to show the advantages of my invention over that one,) the sediment clogs up the discharge-orifice, and that much leakage occurs, after a little use, through the seams at the bottom of the tank. Furthermore, the cost and labor of constructing this hopper-like bottom are much more than with that in my tank.

What I claim as my invention, and desire to secure by Letters Patent, is—

1. An oil or liquid-tank, constructed without any joint at either or all of the points lettered *h i k l* in the drawing, substantially as herein specified.
2. An oil or liquid-tank, provided with a bottom composed of two inclined surfaces, and provided with a depression at about the central point, substantially as and for the purposes herein set forth.
3. The combination, with a tank constructed in either of the above-specified ways, of an enclosing case, of wood or other material, substantially as herein specified.
4. The combination, with said tank for containing oil or other inflammable liquid, of some suitable fire-proof material, substantially as and for the purposes herein specified.

GARRET D. ANDERSON.
